UNITED STATES PATENT OFFICE.

HAROLD JENNINGS KITCHEN, OF LUTON, ENGLAND.

WATER-JACKET FOR ELECTRIC-FURNACE ELECTRODES.

1,254,510.

Specification of Letters Patent. Patented Jan. 22, 1918.

Application filed March 7, 1917. Serial No. 153,118.

To all whom it may concern:

Be it known that I, HAROLD JENNINGS KITCHEN, a subject of the King of Great Britain, residing in Luton, England, have 5 invented certain new and useful Improvements in Water-Jackets for Electric-Furnace Electrodes, of which the following is a specification.

It is usual in electric furnaces of the electrode type to cool the electrodes, where they pass through the roof of the furnace, by water jackets, which rest on and are secured to the roof. In this arrangement there is the drawback that considerable time and 15 labor are spent in removing these jackets, whenever any repairs of the roof are required.

According to the present invention the water jackets are not supported by the roof 20 of the furnace, but are carried by arms adjustable on a vertical support so as to be swung clear of the roof at any time. An adjustment in a vertical direction enables the position of a jacket to be adapted to suit any 25 changes in the height of the roof due to expansion and contraction caused by variations of temperature.

In the accompanying drawing Figure 1 shows in side elevation partly in section and 30 Fig. 2 in end elevation an arrangement according to the invention as applied, by way of example, to a furnace with three electrodes.

The electrodes A, A', A² are surrounded, 35 where they pass through the roof of the furnace, by water jackets B, B', B². Each jacket is supported by arms C', C² (which

are only shown in connection with the jacket B) which are clamped in the required position by screws E', E² to a vertical bar 40 D supported in a bracket F fixed to the side of the furnace G. When it is required to remove a jacket, the corresponding electrode is withdrawn, the jacket raised slightly, if necessary, by lifting the bar D by means of 45 the supporting screw H and swung to one side about the axis of the bar D. The screw H also serves to adjust the position of the water jacket for any variations in the height of the roof. 50

Having thus described the nature of the said invention and the best means I know of carrying the same into practical effect, I claim:—

1. In connection with an electric furnace 55 of the electrode type, water jackets surrounding the electrodes, the said jackets being supported above the roof but free of the latter, so that they can be adjusted in position both laterally and vertically. 60

2. In connection with an electric furnace of the electrode type, water jackets surrounding the electrodes and carried by arms adapted to slide on a vertical support and to rotate about the same, the said jackets 65 being disposed slightly above but free of the roof of the furnace.

In testimony whereof I have signed my name to this specification in the presence of two subscribing witnesses.

HAROLD JENNINGS KITCHEN.
